D8-310. OR D11,205 EX

DESIGN FOR DOOR-KNOB.

Design No. 11,205, dated May 27, 1879

UNITED STATES PATENT OFFICE.

GEORGE S. BARKENTIN, OF HARTFORD, ASSIGNOR TO P. & F. CORBIN,
OF NEW BRITAIN, CONNECTICUT.

DESIGN FOR DOOR-KNOB.

Specification forming part of Design No. **11,205**, dated May 27, 1879; application filed April 17, 1879.
[Term of patent 7 years.]

To all whom it may concern:

Be it known that I, GEORGE SLATER BARKENTIN, of the city of Hartford, in the county of Hartford and State of Connecticut, have originated and produced a new and original Design for a Door-Knob, of which the following is a full, clear, and accurate description, reference being had to the accompanying engraving, making part of this specification.

The form of the knob A is cylindrical. Upon the sides of the cylindrical knob there is a raised molding or bead, c c, which encircles the knob. The recessed part between the beads c c is ornamented by a row of quarterfoils, e, intersected by lozenges f in relief. On the faces of the knob A and rose or plate B there is a raised band at the outer edges g g, inclosing a Maltese-shaped cross, formed by fan-shaped conventional leaves h h, springing from the smaller ring, i, which incloses a circle of quarterfoils, J, and the small cross K, formed by a central dot and four lozenges.

Between each arm of the aforesaid Maltese-shaped cross springs a conventional three-branched fern, l l. All of the above-described ornament is in relief on a dotted ground.

I claim as my invention—

1. In a cylindrical door-knob, the design for sides or edge ornamented with the beads c c, the quarterfoils e, intersected by lozenges f, substantially as above described.

2. In a door-knob, the design for the face of the knob A, consisting of the band g, the Maltese-shaped cross formed by the fan-shaped conventional leaves h h, the circle of quarterfoils J, the central cross K within the ring i, and the conventional three-branched ferns l, combined and arranged substantially as shown and described.

GEORGE SLATER BARKENTIN.
